YARN FEED AND DISTRIBUTOR WHEEL

Henry J. McDermott, Collingdale, Pa., assignor to
American Viscose Corporation, Wilmington,
Del., a corporation of Delaware

Application November 19, 1946, Serial No. 710,859

11 Claims. (Cl. 28—71.5)

1

This invention relates to the feeding and distribution of yarn, strands, threads or other filamentary material onto a moving belt or the like.

The main object of the present invention is to provide an improved device for distributing a yarn, thread, strand or other filamentary material in a regular fashion on a moving belt or the like.

Other objects and advantages of the present invention will become apparent from a study of the following description of the drawings herein.

In the drawings,

Figure 1 is a front view partly in section of an illustrative embodiment of the present invention,

Figure 2 is a top view partly in section of Figure 1,

Figure 3 is a back view of the driving mechanism of this invention, and

Figure 4 is an isometric view of an embodiment of the present invention showing one method of laying filamentary material upon a traveling belt or screen.

As shown in Figures 1 and 2, reference character 1 indicates a rotatable feed wheel mounted on a shaft 3. This shaft 3 is shown as a hollow member in the accompanying drawings. The feed wheel 1 has an apertured thread-carrying periphery. As illustrated in the preferred embodiment, the periphery of the feed wheel 1 is provided with spaced slots parallel to the axis of rotation and it is flanked by a flange that has its inner periphery concentric to the axis of rotation of the feed wheel. An oscillating nozzle 2 is disposed inward of the feed wheel periphery for directing a jet of fluid through the periphery. This fluid may be liquid or gaseous; as shown it is an air nozzle radially extending from the hollow shaft 3 and oscillating therewith.

The hollow shaft 3 is rotatably supported in the supporting member 8 by the bearing members 11 and 12. The bearing members may be roller or journal bearings or just bushings. The main consideration is that the hollow shaft 3 be readily rotatable or oscillatable therein. A conduit 4 which supplies fluid to the nozzle through the hollow shaft is made of an elastic material such as rubber.

Means are provided for oscillating the nozzle 2 and means are provided for rotating the feed wheel 1. As illustrated in the preferred embodiment of this invention, a collar or eccentric disc 5 is suitably mounted on the hollow shaft 3. This collar 5 has a crank pin 13 attached therein, which is connected by a link 6 to a similar crank pin 18 mounted on a slidable block 11, suitably

2

connected on another collar or crank disc 7. This collar which has a driving means 20 integrally connected to it is integrally mounted on the drive shaft 16. The drive shaft 16 is rotatably mounted in the supporting member 8 by the bearing members 14 and 15. The bearing members 14 and 15 may be roller, journal or a plain bushing, the main consideration being that they do not retard the rotation of the drive shaft 16. Suitably mounted on the drive shaft 16 is a sheave or pulley 10 which by virtue of a belt 19 or the like imparts rotation to the feed wheel 1 by a sheave 9 connected thereto. Although a sheave has been shown as a means for driving the feed wheel 1, it is to be understood that these could be geared just as easily. A variable speed adjustment may be incorporated by the use of change gears or variable speed sheaves.

In operation, a yarn, strand, thread or other filamentary material, preferably in a wet condition, is fed over the apertures on the feed wheel 1, adhering thereon and rotating with the feed wheel. The yarn or the like is carried around to the underside of the feed wheel, to a point where it is in contact with the fluid forced through the apertures by the oscillating nozzle 2. As the yarn is freed from the feed wheel it falls into layers due to the oscillation of the nozzle 2 and the rotation of the feed wheel.

Referring to Figure 3, the radial distance from the pin 13 to the center of the collar 5 must always be greater than the radial distance from pin 18 to the center of the collar 7 or oscillation of the nozzle 2 will not take place. However, the stroke of the nozzle 2 may be changed by varying the setting of the slidable block 11 mounted on the collar 7 secured thereon by the set screw 17.

As described in the disclosure, there are two distinct ways of varying the lay of the yarn deposited. One by changing the speed of the feed wheel and the other by changing the stroke of the nozzle.

Although this invention has been described with reference to the improvements shown, it will readily be appreciated that numerous changes may be made without departing from the spirit and scope of the invention as described in the appended claims.

I claim:

1. An apparatus for depositing a strand comprising rotatable means for feeding the strand having an apertured strand-carrying periphery, a nozzle disposed inward of the periphery for directing a jet of fluid through the periphery, means for rotating the feeding means, means

whereby a fluid may be supplied to the nozzle, and means for oscillating the nozzle about an axis within the periphery of the feeding means.

2. An apparatus for depositing a strand comprising a rotatable feed wheel having an apertured strand-carrying periphery, a nozzle disposed inward of the feed wheel periphery for directing a jet of fluid through the periphery, means for rotating the feed wheel, means whereby a fluid may be supplied to the nozzle, and means for oscillating the nozzle about an axis within the periphery of the feed wheel.

3. An apparatus for depositing a strand comprising a rotatable feed wheel having an apertured strand-carrying periphery, a nozzle disposed inward of the feed wheel periphery for directing a jet of fluid through the periphery, means for rotating the feed wheel, means whereby a fluid may be supplied to the nozzle, and means for oscillating the nozzle about an axis within the periphery of the feed wheel, the axis of the feed wheel and the axis of the nozzle being coincident.

4. An apparatus for depositing a strand comprising a rotatable feed wheel having an apertured strand-carrying periphery, a nozzle disposed inward of the feed wheel periphery for directing a jet of fluid through the periphery, means for rotating the feed wheel, means whereby a fluid may be supplied to the nozzle, and eccentric means for oscillating the nozzle about an axis within the periphery of the feed wheel, the axis of the feed wheel and the axis of the nozzle being coincident.

5. An apparatus for depositing a strand comprising a rotatable feed wheel having spaced slots on its strand-carrying periphery, a nozzle disposed inwardly of the feed wheel periphery for directing a jet of fluid through the periphery, means for rotating the feed wheel, means whereby a fluid may be supplied to the nozzle, and eccentric means for oscillating the nozzle about an axis within the periphery of the feed wheel, the axis of the feed wheel and the axis of the nozzle being coincident.

6. An apparatus for depositing a strand comprising a rotatable feed wheel having an apertured strand-carrying periphery, a nozzle disposed inward of the feed wheel periphery for directing a jet of air through the spaced slots, means for rotating the feed wheel, means whereby a fluid may be supplied to the nozzle, and eccentric means for oscillating the nozzle about an axis within the periphery of the feed wheel, the axis of the feed wheel and the axis of the nozzle being coincident.

7. An apparatus for depositing a strand comprising a rotatable feed wheel having an apertured strand-carrying periphery, a nozzle disposed inward of the feed wheel periphery for directing a jet of air through the spaced slots,

means for rotating the feed wheel, means whereby a fluid may be supplied to the nozzle, and eccentric means for oscillating the nozzle about an axis within the periphery of the feed wheel, the axis of the feed wheel and the axis of the nozzle being coincident, and means for varying the stroke of the nozzle.

8. An apparatus for depositing a strand comprising a rotatable feed wheel having spaced slots on its strand-carrying periphery, a nozzle disposed inward of the feed wheel periphery for directing a jet of air through the periphery, driving means comprising a drive shaft, means for rotating the feed wheel connected to the drive shaft, and means for oscillating the nozzle connected to the drive shaft.

9. An apparatus for depositing a strand comprising a hollow shaft, a feed wheel rotatable thereon having spaced slots on its strand-carrying periphery, a nozzle secured to the shaft and disposed inward of the feed wheel periphery for directing a jet of air through the periphery, driving means comprising a drive shaft, means connected to the drive shaft for rotating the feed wheel, means connected to the drive shaft for oscillating the hollow shaft, a conduit connecting the nozzle and bore of the hollow shaft to convey fluid to the nozzle.

10. An apparatus for depositing a strand comprising a hollow shaft, a feed wheel rotatable thereon having spaced slots on its strand-carrying periphery, a nozzle secured to the shaft and disposed inward of the feed wheel periphery for directing a jet of air through the periphery, driving means comprising a drive shaft, means connected to the drive shaft for rotating the feed wheel, a crank disc mounted on one end of the drive shaft, a collar mounted on one end of the hollow shaft and eccentric linkage connecting the collar and disc, and a conduit connecting the nozzle and bore of the hollow shaft to the nozzle.

11. An apparatus for depositing a strand comprising a hollow shaft, a feed wheel rotatable thereon having spaced slots on its strand-carrying periphery, a nozzle secured to the shaft and disposed inward of the feed wheel periphery for directing a jet of air through the periphery, driving means comprising a drive shaft, means connected to the drive shaft for rotating the feed wheel, a crank disc mounted on one end of the drive shaft, a collar mounted on one end of the hollow shaft and eccentric linkage connecting the collar and disc, a conduit connecting the nozzle and bore of the hollow shaft to convey fluid to the nozzle, and a slidable block adjustably mounted on the crank disc and connected to the eccentric linkage to vary the stroke of the nozzle.

Certificate of Correction

Patent No. 2,447,131.

August 17, 1948.

HENRY J. McDERMOTT

It is hereby certified that error appears in the printed specification of the above numbered patent requiring correction as follows:

Column 4, line 1, claim 7, after "feed" for the comma and word ", wheels" read *wheel,;* and that the said Letters Patent should be read with this correction therein that the same may conform to the record of the case in the Patent Office.

Signed and sealed this 28th day of December, A. D. 1948.

[SEAL]

THOMAS F. MURPHY,
Assistant Commissioner of Patents.
